US00D673296S

(12) **United States Design Patent**
Fry et al.

(10) **Patent No.:** **US D673,296 S**
(45) **Date of Patent:** **** Dec. 25, 2012**

(54) **TUBE RELOAD DEVICE**

(75) Inventors: **Kenneth Charles Fry**, San Diego, CA (US); **Scott Edward Curry**, San Marcos, CA (US)

(73) Assignee: **Genesee Scientific Corporation**, San Diego, CA (US)

(**) Term: **14 Years**

(21) Appl. No.: **29/355,175**

(22) Filed: **Feb. 3, 2010**

(57) **CLAIM**

The ornamental design for an tube reload device, as shown and described.

DESCRIPTION

FIG. 1 is an isometric view of a tray portion of a tube reload device shown separately for clarity of illustration showing my new design;

FIG. 2 is a side view thereof;

FIG. 3 is a top view thereof;

FIG. 4 is an opposite side view thereof;

FIG. 5 is another side view thereof;

FIG. 6 is a bottom view thereof;

FIG. 7 is the opposite of another side view thereof;

FIG. 8 is an isometric view of a plate portion of a tube reload device shown separately for clarity of illustration showing my new design;

FIG. 9 is a side view thereof;

FIG. 10 is a top view thereof;

FIG. 11 is an opposite side view thereof;

FIG. 12 is another side view thereof;

FIG. 13 is a bottom view thereof;

FIG. 14 is the opposite of another side thereof;

FIG. 15 is an isometric view of an assembled tube reload device, where the tubes are depicted to show a symbolic break in the length of the tube elements;

FIG. 16 is a top view of an assembled tube reload device;

FIG. 17 is a bottom view of an assembled tube reload device;

FIG. 18 is a side view of an assembled tube reload device where the tubes are depicted to show a symbolic break in the length of the tube elements;

FIG. 19 is an isometric view of a second embodiment of an assembled tube reload device in which the tube elements do not include a symbolic break in their length; and,

FIG. 20 is a side view thereof.

The broken lines are included for the purpose of illustrating portions of the tube reload device that forms no part of the claimed design.

The first embodiment of the tube reload device is shown with symbolic breaks in the length of the rod portions. The appearance of any portion of the article between the break lines forms no part of the claimed design.
